Primary Examiner — Rosemary K Tarcza(74) *Attorney, Agent, or Firm* — Baker Botts L.L.P.(57) **CLAIM**

The ornamental design for a battery module, as shown.

DESCRIPTION

FIG. 1 is a front, top and right side perspective view of a battery module showing our new design;
 FIG. 2 is a rear, bottom and left side perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof; and,
 FIG. 8 is a bottom plan view thereof.

The broken lines in the drawings are for the purpose of illustrating environmental structure and form no part of the claimed design.
